FURNACE CONSTRUCTION

Herbert F. Curtis, Berea, Ohio, assignor to
 Henry Furnace & Foundry Company, Cleve-
 land, Ohio, a corporation of Ohio

Application September 23, 1938, Serial No. 231,365

6 Claims. (Cl. 126—91)

This invention relates to improvements in furnace construction and more particularly to improvement of sectional type furnaces where like sections may be supplied to build up a battery 5 of such sections to form the complete furnace.

Although heating units such as steam radiators have heretofore been constructed whereby they can be made up in any desired number of sections, and furnaces adapted to burn gas have also been 10 of sectional structure, there were many deficiencies in these constructions, which it is the purpose of the present invention in a large measure to overcome.

For instance, such prior furnaces usually required special end sections and special intermediate sections which end and intermediate sections were not interchangeable. By the present invention each section comprises two main section parts or halves which are bolted together to 20 form a section, which sections are alike and may be secured together to form a battery of sections making up the unitary furnace structure.

Furthermore, and what is of still greater importance, was the fact that once assembled there 25 was no means whereby the passages between the combustion chamber and the outlet could be readily cleaned without dismantling the entire furnace. By the present invention there are provided removable sections of the baffles which may 30 be removed through the inlet door and which when removed provide access to all interior parts of the unit without further dismantling of the furnace.

Still other advantages of the invention and 35 the invention itself will become more apparent from the following description of an embodiment, which description is illustrated by the accompanying drawing and forms a part of this specification:

In the drawing: 40 Figure 1 is a vertical elevational view of one of the unit sections, showing the fixed and removable baffles, the removable baffles being shown in section;

Figure 2 is a front elevational view of a battery 45 of sections in assembled position;

Figure 3 is a fragmentary view partly in elevation and partly broken away showing the locking baffle removed and the other removable baffle in 50 the process of being removed;

Figures 4 and 5 are perspective views of the removable baffles.

Referring now to the drawing throughout which like parts have been designated by like reference 55 characters, the furnace illustrated is only the

interior heat exchange structure. The outer housing may be of any desired type and the invention herein resides in the heat exchange unit per se.

Each section of the assembly comprises right and left housing halves 1 and 2 formed to provide inlets 3 disposed at the bottom forward ends and outlets 4 at the top back ends. Each housing half has a peripheral flange 5 from which extend lugs 6. The flanges may be ground so as to provide a tight joint. In this instance, however, a groove 7 is provided in the face of one or more of the flanges in which a suitable sealing gasket or compound may be placed.

The exterior of each section is provided with 15 outwardly extending ribs 8 which provide intimate contact with the air forced around the housing for heat transfer purposes well known.

The inlet openings are relatively large in order 20 that access may be had to the burners and to permit cleaning, etc.

Each outside of the housing sections has a substantially flat machined surface 9 adapted to be juxtaposed and secured to the adjacent housing to permit assembly of the sections into batteries 25 of sections to form any desired size of unit. Rectangular openings 10 extend through the matched sides of the unit which provide means of communication between the separate sections and form a substantially continuous combustion 30 chamber. This provides means whereby separate burners may need only one pilot light which may be supplied at a master section, which is usually the center section, although obviously if only two sections are used it could be either one of the sections. The openings in the outside sections are sealed by suitable plates bolted thereon; or in a three section unit two pilot lights may be provided between the first and second and second and third burners.

The flames from the burners 11 extend upward and the products of combustion impinge against a baffle 12 along which they travel in a generally horizontal direction toward the rear of the unit as indicated by the arrows. Thence they escape 45 around the end of the baffle 12 and pass upward, engaging the baffle 13, where they travel in a substantially horizontal plane toward the front of the unit and escape around the end of the baffle at the front of the furnace. They then rise 50 upward, engaging the top, traveling rearward and escaping at the outlet 4 from where they are conducted by a manifold (not shown) to the chimney flue.

The baffles 12 and 13 are formed integral with 55

the housing and comprise inwardly extending flanges on each housing, which abut at their edges to bridge the space across the housing. The baffle 13 extends from the back wall to a point spaced from the front of the housing and the baffle 12 extends from a point spaced from the back wall to a point spaced from the front of the housing, all as is best illustrated in Fig. 1.

It being desirable to close the space between the forward end of the baffle 12 and the front of the housing, in order that the combustion products do not escape directly to the top of the housing, a baffle 15 is provided. This baffle is best shown in Fig. 4 and is provided with an offset end 16 for engagement with the front end of the baffle 12, and a curved body portion 17 which connects to a downwardly depending portion 18. This baffle rests on curved flanges 19 of the same contour as the baffle, which flanges are integral with and extend inwardly from each side of the housing. Means for holding the baffle 15 securely in place on the flange is provided, which means further closes off the combustion chamber from the forward upper end of the housing, and includes a second removable baffle 20, as best shown in Fig. 5. One end of the baffle 20 rests on the forward side of the housing and the other end seats on a transverse rib 21 formed integral with the baffle 15. As in the case of the baffle 15, ribs 22 are provided on the side of the housing. The handle 23 is provided for the baffle 20 extending from the underside of the baffle toward the housing inlet 3.

It will thus be seen that the removable baffles provide an interlocking engagement which securely holds the same in place and that they thus close off the front end of the housing between the front end and the baffle 12. The downwardly depending portion 18 also directs the products of combustion in an upward and rearward direction.

It is to be noted that the baffles extend downward slightly in the direction of flow of the products of combustion. This causes a more intimate contact of said products with not only the baffles but the housing walls, slightly retarding the flow and assisting in effecting a greater heat exchange from the combustion products to the housing.

It should be particularly noted that by this arrangement the baffle 20 can be removed by grasping the handle 22, up-ending the same and withdrawing it through the opening 3, as shown by the dotted lines in Fig. 1. When the baffle 20 is removed, the baffle 15 may then be removed in a similar manner, the part 21 furnishing a good hand hold for manipulating the same. The baffle 15 is shown in the process of removal in Fig. 3.

It will thus be seen that when the baffles are removed, which removal may be readily accomplished through the opening 3, that full access is had to all parts of the housing whereby accumulated soot and dust may be readily removed and the interior parts thoroughly cleaned without the use of special tools.

Having thus described my invention in an embodiment thereof, I am aware that numerous and extensive departures may be made from the exact structure shown. It is not my intention, however, to limit my invention to this exact structure other than is delineated in the accompanying claims, and that the claims should be construed with the range of equivalents to which they are entitled in view of the prior art.

I claim:

1. A heater of the class described including a housing comprising matched right and left-hand sections, said housing being formed to provide an inlet at the bottom and an outlet at the top, inwardly extending portions on said housings adapted to abut each other and to provide baffles extending across said housing, said baffles being arranged to provide a sinuous horizontal flow for the products of combustion from the inlet to the outlet, said baffles being interrupted adjacent one end and removable plates being provided to close the baffles at the point of interruption.

2. A heater of the class described including a housing comprising matched right and left-hand sections, said housing being formed to provide an inlet at the bottom and an outlet at the top, inwardly extending flanged portions on said housing adapted to abut each other to provide baffles extending transversely across the housing, said baffles being arranged to cause a sinuous flow for the products of combustion in horizontal planes disposed one above the other, at least one of said baffles being interrupted at one end to provide an opening, a removable plate disposed over said opening, a second removable plate engaging the wall of the housing and the first plate to lock the first plate in position and to provide a further baffle for the products of combustion.

3. A heating unit of the class described comprising right and left-hand housing sections adapted to be secured together to provide a combustion and heat transfer chamber having an inlet and an outlet, each of said sections having inwardly extending ledges adapted to abut each other when the housing is assembled to provide partitions extending across the housing, said partitions being arranged to cause the products of combustion to travel in vertically spaced horizontal planes from the front to the rear and rear to the front of said housing, said baffles being formed to provide an opening at the front of the housing and a removable baffle plate for closing said opening, said baffle plate being removable through the housing inlet, a second removable baffle plate adapted to engage said first baffle plate and the housing wall to hold said first baffle in position and also being removable through said inlet.

4. A furnace comprising matched left and right housing portions adapted to be placed together to form a housing section, said sections formed with faces disposed on opposite sides of each section and adapted to be matched with each other and formed to provide openings therethrough, said sections adapted to be assembled in juxtaposition to each other in batteries with said openings in alignment to provide a unitary structure, burners disposed in said sections and communicating with each other through said openings, each of said housing portions having inwardly extending flanges adapted to abut each other to form partitions in the housings, said partitions being arranged to cause a continuous sinuous flow of the products of combustion through the housing, at least one of said partitions being interrupted to provide a cleanout opening, and a removable baffle for closing said opening and a second removable baffle for locking said first baffle in place and further closing said opening.

5. In a structure of the class described, a housing formed to provide an inlet and outlet and a combustion chamber, substantially horizontally extending baffles provided above said combustion

chamber for causing the products of combustion to flow in horizontal planes disposed above each other from the inlet to the outlet, one of said baffles being interrupted at the inlet opening of the furnace and the wall of the housing provided with a guide flange, a removable baffle of curved conformation bridging said flanges and resting on said horizontal baffle and having a downwardly depending portion spaced from the front wall of the housing, a transverse ledge on said curved baffle and a second removable baffle plate having one end adapted to engage said ledge and the other end to engage said housing to lock said first removable baffle in place and close the housing from the inlet, said baffles being easily removable to provide ingress to the housing between said baffles for cleaning and inspection purposes.

6. A heater of the class described including a housing comprising matched right and left-hand sections, said housing being formed to provide an inlet at the bottom and an outlet at the top, inwardly extending portions on said housings adapted to abut each other and to provide baffles extending across said housing, said baffles extending from the front to the rear of the housing and inclined downwardly in the direction of the flow of the gases to provide a substantially horizontal flow for the products of combustion from the inlet to the outlet planes spaced one above the other, said baffles being interrupted adjacent one end and removable baffles being provided to close the first mentioned baffles at the point of interruption.

HERBERT F. CURTIS.
